UNITED STATES PATENT OFFICE.

JOHN W. ENRIGHT, OF NEW ORLEANS, LOUISIANA.

STATIONARY CHEMICAL-MIXING FIRE-EXTINGUISHER SYSTEM.

Application filed November 23, 1920. Serial No. 426,021.

To all whom it may concern:

Be it known that I, JOHN W. ENRIGHT, a citizen of the United States of America, residing at New Orleans, in the parish of Orleans and State of Louisiana, have invented certain new and useful Improvements in Stationary Chemical-Mixing Fire-Extinguisher Systems, of which the following is a specification.

10 This invention relates to stationary chemical mixing fire extinguisher systems, which are devoid of moving mechanical parts, and operate automatically under fire emergency conditions. The objects of the invention, are 15 to insure the prompt and certain automatic operation of the system and to insure a regular and continuous supply of acid to the alkaline solution, thereby providing for the discharge of substantially the entire volume 20 of alkaline solution at a substantially uniform pressure.

In the illustrative embodiment of the invention shown the system includes the usual tank 1, for an alkaline solution, and a riser 25 2 extending from said tank throughout the height of the building. In the embodiment disclosed, the riser is connected at its upper end to a reservoir 16, which is in turn connected to the upper end of a stand-pipe 15, 30 from which extend the leaders or laterals 17 carrying the sprinkler heads or distributing valves 18. The reservoir 16, stand-pipe 15, and leaders or laterals 17, are filled with an extinguishing liquid, preferably of a non-freezing character. The lower end of the stand-pipe 15, projects into a reservoir 6 containing mercury. The system also includes 35 a container 5, which connects to the reservoir 6 by a pipe 14, the pipe 14 extending into the mercury in the reservoir 6; the system also includes a discharge pipe 10 for discharging liquid from the container 5, and connects therewith through the pipes 14 and 40 13 which form a trap for a mercury seal; a 45 vent pipe 22 also connects the pipe 10 with the upper end of the container 5. The system also includes a primary acid receptacle 3, which is preferably arranged in an extension 7 of the tank 1, located at its upper 50 side thereof. The primary acid receptacle 3, incloses an acid discharge siphon-pipe 8, projecting externally of said receptacle and discharging into the tank 1.

The amount of acid discharged from the 55 primary acid receptacle being sufficient to

generate the initial working pressure. The system also includes a secondary acid receptacle 4, located in the extension 7, of the tank 1, which encloses a discharge pipe 9, discharging at its upper end into the tank 1. The air space in the secondary acid receptacle normally has free and unrestricted communication with the air space in the tank 1, for preventing pressure differences, this communication consists of a pipe 12 and a trap 21 into which mercury is discharged under fire emergency conditions, to seal said communication as will be explained later. The system also includes a reservoir 11, having a discharge outlet in its bottom, forming a trap 19 for a mercury seal. The discharge outlet connects to the trap 21, and discharges through the outlet 23, into the tank 1. The discharge siphon leg 8, extends into said reservoir; and the discharge pipe 10, discharges into the reservoir 11.

The operation of the system is as follows:—

After the tank 1 has been filled with the requisite amount of alkaline solution, and acid has been placed in the primary receptacle 3, and secondary receptacle 4, and mercury has been placed in the reservoir 6, and trap 19, the reservoir 16, the stand-pipe 15, and leaders or laterals 17, are filled with extinguishing liquid, the weight of this liquid is effective to displace the mercury in the reservoir 6, i. e.: to force a column of mercury up pipe 14, into the trap 13. The container 5, thereupon is filled with a liquid, and the system is now ready for operation.

With a sprinkler head or distributor valve 18, is opened under fire emergency conditions, the extinguisher liquid in reservoir 16 is discharged and the pressure on the mercury in the reservoir 6, is relieved with the result that the mercury column recedes from the trap 13 allowing the liquid in the container 5 to flow through the trap 13, and pipe 10 into the reservoir 11 where it is retained by the mercury seal in trap 19, the liquid rising in the leg of the siphon-pipe 8, as it rises in the reservoir 11, until its weight overcomes the mercury seal in the trap 19, the mercury discharging into the trap 21 and sealing the communication between the air spaces of the secondary acid receptacle and the tank 1, the liquid passing from the reservoir 11, into the tank 1, through the outlet 23, the discharge of

liquid from the reservoir 11 and siphon-pipe 8, creating a suction impulse in the siphon-pipe 8, sufficient to initiate the siphoning of acid from the primary receptacle 3, the acid passing through the trap 19, and outlet 23, into the tank 1, the vent 20 preventing pressure differences between receptacle 3, and tank 1. The high pressure gases generated in the solution tank 1, consequent to the mixing of the chemicals, passes through the pipe 9 to the secondary receptacle 4, where it is trapped by the mercury seal in the trap 21 and becomes effective to eject acid from the secondary acid receptacle as soon as the pressure in the tank falls below the trapped pressure in the secondary acid receptacle. In this way the operation of the system is maintained continuously, and at a substantially uniformed rate of pressure. The high pressure passes through pipe 10, 13, and 14, and entering reservoir 6, forces a column of mercury up pipe 15. This column of mercury acts as a seal to prevent the escape of high pressure gases into the leaders or laterals 17. Heretofore, the siphoning of acid was initiated by a suction impulse or pressure difference transmitted to the acid by a suction pipe connection between the acid receptacle and the upper end of the distributing system. This required considerable piping especially where the system is installed in a very high building and where slight leakage in the suction pipe may easily render the system inoperative. In my invention, I use no connection whatsoever between the distributing system and the acid receptacle.

Having fully described my invention I claim.

1. In a stationary chemical mixing fire extinguisher system, a tank for an alkaline solution, a reservoir for a liquid medium having a discharge outlet, a mercury seal normally interposed in said outlet, an acid receptacle having a discharge siphon pipe, one leg of which extends into the said reservoir, and means operative under fire emergency conditions for charging said reservoir with liquid, the liquid entering said siphon leg, the weight of the liquid ultimately overcoming the mercury of said seal and discharging therefrom, the discharge of the liquid from the reservoir and siphon leg initiating the siphoning of acid from the acid receptacle.

2. In a chemical mixing fire extinguishing system, a tank for an alkaline solution, a reservoir for a liquid medium, an outlet for said reservoir, a mercury seal controlling said outlet, an acid receptacle having a discharge siphon pipe having a leg extending into the said reservoir, a container for a liquid medium, a mercury trap controlling the outlet of said container, a

distributing pipe containing fluid which is utilized to maintain the mercury trap normally operative as a seal for said outlet, a pipe through which the liquid flows from said container to said reservoir under fire emergency conditions, the weight of said liquid overcoming said seal, initiating the siphoning of acid from said receptacle when the liquid is thus automatically discharged from said reservoir.

3. In a chemical mixing fire extinguishing system, a solution tank, an acid receptacle having a discharge siphon pipe, co-operating means operating on the emergency condition of the system for charging the siphon pipe with a liquid element, means for discharging the liquid element from the siphon pipe, the discharge of the liquid element initiating the siphoning of acid from the acid receptacle.

4. In a chemical mixing fire extinguishing system, a distributor system, a connected solution tank, an acid receptacle, means of communication between the air spaces of said receptacle and tank, said means comprising a pipe, and a trap for a body of mercury, a reservoir for a liquid element, a discharge outlet for said reservoir, a mercury seal in said discharge outlet and liquid means operating on the emergency condition of the system for ejecting the mercury seal from the discharge outlet and discharging said mercury into said trap for sealing said communication between the air spaces of said receptacle and tank.

5. In a chemical mixing fire extinguishing system, a distributor system, a tank for an alkaline solution, a reservoir for a liquid element, an acid receptacle having a discharge siphon pipe having a discharge leg extending into said reservoir, and means acting under fire emergency conditions for discharging a liquid into the said reservoir and discharge leg, and means for discharging said liquid from said leg for initiating the siphoning of acid from said receptacle.

6. In a chemical mixing fire extinguishing system, a distributor system, a connected supply tank, and an acid receptacle, means of communication between the air spaces of the supply tank and acid receptacle, a liquid element operating on the emergency condition of the system to seal said communication for trapping high pressure gases in the acid receptacle, a pipe for discharging acid from said receptacle, said acid discharge being influenced by the trapped high pressure gases.

7. In a chemical mixing fire extinguisher system, a tank for an alkaline solution, an acid receptacle, a connected siphon discharge pipe means operable under fire emergency conditions for putting a liquid in said siphon discharge pipe and means displaceable by the weight of said liquid for

permitting the outflow of said liquid, thereby creating a suction impulse and initiating the siphoning of acid from said receptacle.

8. In a chemical mixing fire extinguisher system, a distributor system, a tank for an alkaline solution, a liquid container, an acid receptacle, means acting under fire emergency conditions for discharging liquid from said container into said tank and means whereby the discharge of the liquid into said tank initiates the discharge of acid from said receptacle.

9. In a chemical mixing fire extinguisher system, a tank for an alkaline solution, a reservoir for a liquid medium, an acid receptacle having a siphon discharge pipe the discharge leg of which terminates in said reservoir, means acting under fire emergency conditions for charging said reservoir and said discharge leg, means controlling the outlet to said reservoir displaceable by the weight of the column of liquid in said reservoir to permit discharge of said liquid therefrom, thereby creating a suction impulse in the siphon discharge pipe sufficient to initiate the siphoning of acid from said receptacle.

10. In a chemical mixing fire extinguisher system, a tank for an alkaline solution, a container for a liquid medium, a normally empty reservoir, an acid receptacle provided with a discharge siphon-pipe having a

discharge leg extending into said reservoir, means acting under fire emergency conditions for discharging said liquid medium into said reservoir and a discharge leg, and means for controlling the outlet of said reservoir and displaceable by the weight of said liquid in said reservoir to permit discharge of said liquid therfrom, thereby creating a suction impulse in said siphon discharge pipe, for initiating the discharge of acid from said receptacle.

11. In a chemical mixing fire extinguisher system, a tank for an alkaline solution, a normally empty reservoir, having a mercury seal in its discharge outlet, an acid receptacle having a discharge siphon-pipe extending into said reservoir, means acting under fire emergency conditions for discharging liquid into said reservoir, the weight of said liquid ultimately overcoming the mercury of said seal and discharging therefrom the discharge of liquid from said reservoir creating a suction impulse in the discharge siphon-pipe.

In testimony whereof I have hereunto set my hand in presence of two subscribing witnesses.
